United States Patent Office

Des. 231,881
Patented June 25, 1974

231,881

BED HEADBOARD

Roland P. Carter, Lynchburg, Va., assignor to The Lane
Company, Inc., Altavista, Va.

Filed July 17, 1973, Ser. No. 379,943

Term of patent 14 years

Int. Cl. D6—01

U.S. Cl. D6—79

Fig. 1.

FIG. 2.

FIG. 1 is a front perspective view of a bed headboard showing my new design; and

FIG. 2 is a front elevational view.

The rear of the headboard is plain and unornamented.

I claim:

The ornamental design for a bed headboard, as shown and described.
